UNITED STATES PATENT OFFICE.

BYRON PHELPS, OF SEATTLE, WASHINGTON.

LOCK.

SPECIFICATION forming part of Letters Patent No. 722,622, dated March 10, 1903.

Application filed September 23, 1901. Serial No. 76,313. (No model.)

To all whom it may concern:

Be it known that I, BYRON PHELPS, a citizen of the United States, residing at Seattle, in the county of King and State of Washington, have 5 invented a new and useful Lock, of which the following is a specification.

My invention relates to locks of a general construction, such as shown in a former patent of mine, No. 631,434, dated August 22, 1899; 10 and my object is to provide a simple and improved locking mechanism, also to provide an improved latch mechanism.

Other desirable objects are attained which are obvious to one skilled in the art.

15 Figure 1 is a plan view. Fig. 2 is a side view of detached portions. Fig. 3 is a detail.

A is a frame having extensions B B'. These extensions are in the form of sleeves and provide suitable bearings for an inner-spindle C 20 and an outer spindle C'.

D is a knob carried by the inner spindle C, and D' is a knob carried by the outer spindle C'. The spindle C carries a roll-back E, while spindle C' carries a roll-back E'.

25 F is a yoke having a shank F' and connected to a latch G. Roll-backs E E' are normally in engagement with the yoke F and are adapted to actuate the yoke when a knob is turned.

30 I have provided the following improved mechanism whereby the latch G may be swung in flush with the frame without moving or disturbing any of the mechanism of the lock.

35 The shank F' has an elongated slot F². G' is a pin carried by the latch G and which projects into the slot F².

F³ is a pin carried by the shank F'. F⁴ is a spring interposed between pin F³ 40 and latch G.

F⁵ is a spring preferably stronger than spring F⁴ and interposed between pin F³ and the frame A.

45 When the door is being closed, the latch-bolt G rubs against the strike (not shown) and is moved in, compressing the spring F⁴, but not moving the shank F', which is held in place by the heavier spring F⁵. When, however, the shank is drawn in by turning a 50 knob, the pin F³ compresses the spring F⁵, which when the knob is released restores the shank to position.

If desired, a single spring could be used in place of the two shown and could be separated by the pin F³ into two parts, one of 55 which might have more coils than the other, thus giving a stronger pressure on one side of the pin F⁸ and a lighter pressure on the other side, which would give the same effect as the employment of springs of different 60 strengths.

H is a rock-shaft pivoted to the frame A and having an arm H' and a nose H².

H³ is a flat spring which bears against the nose H² and serves to hold the shaft in its extreme positions.

J is a reach-rod one end of which is supported by being pivotally connected to the arm H'.

K is a pin carried by the rod J and which 70 is slidably mounted in the frame A:

L is an opening in the spindle C and adapted to receive the pin K when the spindle C is rotated so as to bring the opening L into alignment with the pin K.

75 M is a key mechanism in the outer knob D.

M' is a key mechanism in the inner knob D'.

N is a key-rod extending from the key mechanism M, to which it is attached, through the spindle C. A similar key-rod N' extends 80 from key mechanism M' through spindle C'. From the end of key-rod N projects an eccentrically-located pin O. A similar pin O' projects from rod N'.

P is a notch in one end of the reach-rod J. 85

Q is an extension from reach-rod J, which plays back and forth in a guide-hole R in the frame A and helps to guide the movement of the reach-rod J.

The spindle C may be locked from either 90 side of the door by means of a key. Thus assume that a key is inserted in key mechanism M and turned, the rod N turns and its pin O sweeps around, (turning clockwise in Fig. 2,) enters the notch P and moves the 95 reach-rod J to the left and with it the pin K, which enters the hole L in spindle C, thus locking the same. The parts are then in the position shown in dotted lines, Fig. 2. The pin O' operates in precisely the same manner 100 to lock the spindle C when the key is used in key mechanism M'.

It will be seen from the foregoing that the mechanism can only be operated by a key,

that the key can operate through either knob, and that the outside knob may be locked without locking the inner knob. Therefore this form of lock is particularly adapted for 5 use in public buildings, churches, &c. For instance, the janitor may lock the outer knob and leave the building without danger of imprisoning any person who may be left inside. Those inside may turn the knob to operate 10 the latch to open the door, but persons cannot enter from the outside unless provided with a key, as the outer knob is locked. Moreover, it is impossible to disturb the proper working of the mechanism, as there 15 are no finger-pieces or buttons or the like to tamper with. This makes the lock particularly desirable for the purpose mentioned. Obviously in unlocking the spindle C the parts move in a reverse direction.

20 I do not desire to limit myself to the specific construction shown, as many changes may be made without departing from the spirit of the invention.

What I claim is—

- 25 1. A frame, a latch-bolt, an outer and an inner spindle, latch mechanism connecting said bolt and spindles, a locking-pin slidably mounted in said frame, said outer spindle having means adapted to engage said pin, and 30 key mechanism in each of said spindles engaging with means for moving said pin.
2. A frame, a latch-bolt, an outer and an inner spindle, latch mechanism connecting said bolt and spindles, a locking-pin slidably 35 mounted in said frame, an opening in said outer spindle to receive said pin, and key mechanism operating through either of said spindles to actuate said pin.
3. A frame, a latch-bolt and outer and inner spindles connected with mechanism to 40

operate said latch-bolt, one of said spindles having a hole therein, a reach-rod having a pin, said pin being slidably mounted in said frame, and a key mechanism operating through either of said spindles to move said 45 reach-rod and pin transversely of said spindles and cause said pin to enter said hole.

4. A frame, a latch-bolt, latch mechanism, an outer spindle, an inner spindle, said outer spindle having a transverse hole therein, a 50 reach-rod having a locking-pin thereon, said pin being slidably mounted in said frame, said reach-rod having a notch, a plurality of key-rods each having an eccentric-pin adapted to enter said notch and move said reach-rod. 55

5. A frame, a latch-bolt, a shank, means for operating said shank, the end of said shank having a slot, a pin on said latch-bolt lying in said slot, a spring-retaining means on said shank, a spring extended between said spring- 60 retaining means and said latch-bolt, and a spring between said spring-retaining means and a part of said frame, one of said springs being stronger than the other.

6. A frame, a latch-bolt, latch mechanism, 65 an outer spindle, an inner spindle, said outer spindle having a transverse hole therein, a reach-rod, a locking-pin thereon, said reach-rod having a notch, a plurality of key-rods each having an eccentric-pin adapted to enter 70 said notch and move said reach-rod, a rock-arm connected to one end of said reach-rods, the other end of said reach-rod having an extension slidably mounted in said frame.

Signed at New Britain, Connecticut, this 75
23d day of August, 1901.

BYRON PHELPS.
